UNITED STATES PATENT OFFICE

124,501

DESIGN FOR A DRESS

Murray M. Schwalbaum, New York, N. Y.

Application November 13, 1940, Serial No. 96,560

Term of patent 3½ years

To all whom it may concern:

Be it known that I, Murray M. Schwalbaum, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design, and

Fig. 2 is the rear view thereof.

I claim:

The ornamental design for a dress, substantially as shown.

MURRAY M. SCHWALBAUM.
